PROPELLER BLOWER APPARATUS

Alexander I. Ponomareff, Drexel Hill, Pa., assignor
to Westinghouse Electric & Manufacturing
Company, East Pittsburgh, Pa., a corporation of
Pennsylvania

Application April 15, 1939, Serial No. 267,978

5 Claims. (Cl. 230—116)

My invention relates to propeller blowers and it has for an object to provide apparatus of this character capable of developing relatively high static pressures.

5 A further object of my invention is to provide apparatus of the above character capable of developing high static pressures while keeping the rotational speed and the noise level at relatively low values.

10 In the application of propeller blowers for forced draft purposes, the demand for high static pressures has been increasing in an effort to increase the combustion rate, and, therefore, for a combustion and steam generating equipment occupying a given space, to increase the steam production rate. This trend was responsible for the manifestation of the problem of recirculation in an acute way and which, but for the solution by means such as disclosed and claimed in the application of Flanders, Serial No. 163,727, filed September 14, 1937, and assigned to Westinghouse Electric & Manufacturing Company, would have been a serious obstacle to further increase in static pressure. As propeller speeds and static pressures tend to increase noise becomes more and more objectionable; and, in my application, Serial No. 176,899, filed November 27, 1937, and assigned to Westinghouse Electric & Manufacturing Company, there are disclosed and claimed several features contributing to operation with reduced noise. Among such features are: a projected blade area ratio of 100% or more, the use of six or more blades and a blade length order of 25% or less of the propeller diameter, the provision of discharge-side airfoil guide vanes having blunt and rounded inlet edges to permit of efficient operation throughout a wide range of angles of attack of entering air, spacing of such airfoil guide vanes from the discharge edges of the propeller blades from 9 to 20% of the propeller diameter, the use of a special splitter and guide vane arrangement in the blower discharge elbow section, and operation of the blower below the critical speed afforded by the various features contributing to high efficiency.

45 It is also old, as disclosed in British Patent No. 194,317 of June 5, 1924, to provide inlet guide vanes for imparting rotary movement to entering fluid in a direction opposite to the direction of rotation of the blades of a propeller or fan for the purpose of reducing or eliminating the rotational component of air issuing from the propeller or fan to secure more efficient operation.

50 I have found that inlet guide vanes utilizing the general principles disclosed in the British patent

may be advantageously combined with features referred to in my application aforesaid, the combined arrangement securing, not only increased static pressures and efficiencies, but such increases with reduced propeller speeds and noise. Improved performance in these respects is due to the joint effect of inlet and discharge guide vanes in removing the rotational component imparted to the air by the propeller, the inlet passage for the propeller having guide vanes arranged to impart a rotational component of motion to the air supplied to the propeller such that the rotational component of air leaving the propeller is reduced through a wide range of blower capacity at a constant speed and the discharge passage having 15 guide vanes curved so as to eliminate the remaining rotational component of motion of air leaving the propeller discharge edges. With this arrangement of inlet and discharge guide vanes it is assured that an otherwise excessive rotational 20 component given by the propeller is efficiently converted without excessive turning by either set of guide vanes. Furthermore, over a range of blower capacities, the presence of the inlet guide vanes assures of reduced variation in the rotational 25 component of air leaving the propeller in consequence of which the angle of approach of air entering the discharge guide vanes is narrowed; and, as the discharge guide vanes are preferably of airfoil section having rounded blunt 30 inlet edges permitting of efficient operation throughout a wide range of angle of attack of the entering air, they are capable of handling air efficiently with a minimum of shock, turbulence or eddying over a considerable capacity range of 35 the blower, the rotational component or twist of the air discharged from the propeller changing with change in capacity for a given speed.

40 As the propeller has a uniform radial pitch and as the axial pitch of the blades increases from the leading to the trailing edges, the air would be discharged therefrom with an increasing rotational component or twist from the blade tips to the hub unless compensatory measures were taken so that the air may be discharged from the 45 propeller at a more uniform angle from the blade tips to the hub, and, therefore, be susceptible of being handled more efficiently by the discharge guide vanes. To this end, a vortex chamber is provided between the inlet guide vanes and the 50 propeller, the vortex chamber being arranged so that air traversing it from the discharge edges of the inlet guide vanes to the inlet edges of the propeller blades is given a variable twist or rotational component from the blade tips to the hub 55

in order to reduce the variation otherwise occurring at the discharge side of the propeller.

The inlet passage is provided with a circumferentially-extending vane, such as disclosed and claimed in the aforesaid Flanders application, with the result that recirculation, which would otherwise occur and cause disturbance of the flow conditions given to the air in the inlet passage due to the cooperation of the inlet guide vanes 5 and the vortex chamber, is resisted.

Accordingly, therefore, a further object of my invention is to provide a propeller blower having inlet and discharge guide vanes with the discharge guide vanes each having an airfoil section 15 with a relatively blunt inlet edge.

A further object of my invention is to provide a propeller blower having inlet and discharge guide vanes with a vortex or whirl chamber arranged between the inlet guide vanes and the 20 propeller.

A further object of my invention is to provide pre-twist guide vanes with circumferentially-extending vane means cooperating with the propeller blade inlet edges to resist recirculation and 25 consequent pressure pulsations.

These and other objects are effected by my invention as will be apparent from the following description and claims taken in connection with the accompanying drawings, forming a part of 30 this application, in which:

Fig. 1 is a longitudinal sectional view of my improved blower;

Figs. 2, 3 and 4 are detail sectional views taken along the lines II—II, III—III and IV—IV of Fig. 1, respectively;

Fig. 5 is a transverse sectional view taken along the line V—V of Fig. 1 and viewed in the direction of the arrows;

Fig. 6 is a plan view of the blower outlet as 40 viewed upwardly from the line VI—VI in Fig. 1 and looking in the direction of the arrows;

Fig. 7 is a transverse sectional view taken along the line VII—VII in Fig. 1, looking in the direction of the arrows and with a portion of 45 the outer casing removed and the circumferential vane partially broken away to show the inlet vanes in greater detail;

Figs. 8 and 9 are detail sectional views along the lines VIII—VIII and IX—IX, respectively, of 50 Fig. 1;

Fig. 10 is a sectional view taken along the line X—X of Fig. 1;

Fig. 11 is a developed view of the guide vanes and the propeller blade at the tip of the latter, taken along the line XI—XI of Fig. 1;

Fig. 12 is a view similar to Fig. 11 but showing a development at the root of the blade, taken along the line XII—XII of Fig. 1; and,

Fig. 13 is a graph indicating both improved 60 efficiency and static pressures due to the provision of the inlet and discharge guide vanes.

In the drawings, there is shown a propeller, at 10, including a hub 11 and blades 12, and a stator structure, at 13, having a circular wall element 14 defining close clearance with the blade tips and cooperating with the hub to form the blade space, at 15, the latter space, preferably, forming the throat portion of the converging-diverging flow passage within which the propeller is arranged.

The propeller is preferably of uniform radial pitch and the axial pitch increases from the inlet to the trailing or discharge edges of the blades.

The stator structure has an inlet passage, at 75 16, for supplying fluid to the propeller, and a dis-

charge passage 17 for conducting fluid away from the propeller, the adjacent inlet and outlet ends of the passages being close to and aligned with ends of the blade space; and, as the inlet passage converges toward the propeller and the outlet passage diverges away therefrom, it will be seen that the blower passage has no precipitous change in area and that it provides for efficient conversion of velocity into pressure.

The inlet passage, at 16, has a circumferential series of guide vanes 18 arranged therein and functioning to impart a rotational component to the entering air so that the rotational component of air issuing from the propeller blades 12 is reduced, the residual rotational component of air discharged from the propeller being removed by the circumferential series of discharge vanes 19 arranged in the discharge passage, at 17.

As it is desirable to provide for efficient operation over a wide capacity range, the guide vanes 20 19 are of airfoil section and have rounded blunt inlet edges, as shown in Figs. 10, 11 and 12, permitting of efficient operation throughout a wide range of angle of attack of the entering air with the result that, even though the angle of the air 25 may vary through a substantial range, due to variation in blower capacity, the discharge guide vanes are nevertheless capable of acting on air to convert efficiently the rotational component of motion into axial motion without shock or eddy- 30 ing.

To avoid a resonant condition and consequent noise, the relative numbers of inlet guide vanes 18, propeller blades 12, and discharge guide vanes 19 are arranged such that the blades of the propeller and the vanes of either or both of the guide vane groups do not have a common factor. For example, with seven propeller blades, there may be nine inlet guide vanes and eight discharge 35 guide vanes.

As the propeller blades tend to impart a variable twist or rotational component to the air issuing from the discharge edges from the tips to the hub, the twist or rotational component increasing with reduction in radius, the discharge edges 21 of the inlet guide vanes are not only arranged to give a certain amount of twist or rotation to the entering air but such edges are spaced ahead of the inlet edges of the propeller blades and converge outwardly relatively to the plane of rotation of the latter to provide a vortex chamber 22, the vortex chamber being approximately trapezoidal in cross section, thereby providing an increasing arc of travel between the inlet guide vane discharge edges and the propeller blade inlet edges, the arc being a minimum for the tips of the blades and a maximum for the roots of the latter, this being the proper relation for securing an increasing rotational motion with reduction in radius. The vortex chamber 22, therefore, serves to give an increasing rotational component to the air and toward the propeller axis to compensate for the increasing twist or angular component that would otherwise occur at the discharge side of the blades as the hub is approached, with the result that air discharged from the propeller has a minimum of variation of angle of discharge from the tips to the roots of the propeller blades so that the air may be better handled by the guide vanes with effective and 50 efficient conversion of the rotational component of motion into axial motion with a corresponding increase in static pressure.

A circumferential vane 23 having its discharge edge 24 arranged transversely of and continu- 55 70 75

ously to the inlet edges of the propeller blades, the vane 23 serving to prevent recirculation of air and which recirculation would otherwise upset the flow conditions imparted by the guide vanes 18 and the vortex chamber 22 to the air entering the propeller, traverses the vortex chamber in the direction of flow and is preferably carried by the inlet guide vanes. As shown, the vane 23 is preferably carried by the guide vanes 18 and extends rearwardly of the latter so that its discharge edge defines close clearance with respect to the propeller blade inlet edges.

The prime mover or the turbine, at 25, for driving the propeller, at 10, is arranged at the suction side of the latter so as not to interfere with entrance and flow of air toward the propeller. Accordingly, the stator structure, at 13, embodies an outer casing or housing, at 26, including straight and elbow sections 27 and 28, respectively, and inner core members or elements 29 and 30, whose adjacent ends are aligned with the propeller hub 11 at the inlet and discharge sides of the latter. The straight section 27 includes a converging portion 31 joined by the throat wall element 32 to the diverging portion 33, the latter connecting with the elbow section 28. The converging portion 31 is curved in the direction of flow to present an outer convexo-conical surface 34, and the inlet core member 29 is similarly curved to present an inner concavo-conical surface 35, this arrangement of boundary surfaces providing for convergence of the inlet passage, at 16, from the circumferential inlet 36 having a large component of radial direction to its outlet having a large component of axial direction and the construction and arrangement of the inlet passage providing adequate admission area and streamline flow with gradual convergence toward the propeller both in direction and in area. Furthermore, the turbine, at 25, may be located quite close to the propeller so that the latter may be supported in an overhung manner by means of the turbine bearings 37 and 38, the end of the turbine spindle 39 adjacent the propeller, as well as the adjacent bearing 38, being encompassed by, or telescoped with respect to, the inlet core member 29 with the result that the adjacent bearing 38 is arranged relatively close to the propeller.

The prime mover or turbine, at 25, and the propeller, at 10, are supported directly and independently of the blower stator structure, at 13, with the result that the latter is relieved of load and working stresses due to the prime mover and the propeller. To this end, the turbine is shown as provided with a supporting foot construction 40 carried by the bedplate 41, and the blower stator structure, at 13, may be supported in any suitable manner so long as the outer casing 26 has the throat portion thereof concentric with the propeller. As shown, the stator structure is carried and held in aligned relation with the propeller by supports 42 and 43, the support 42 being mounted on the bedplate 41 and the support 43 being constituted, for example, by a bulkhead.

The inlet guide vane outer and inner edges are preferably attached to the converging portion 31 of the outer casing and to the inlet core member 29, respectively. Likewise, the outer and inner edges of the discharge guide vanes are connected to the diverging portion 33 of the straight section and to the core member 30, respectively.

As disclosed and claimed in my application aforesaid, the elbow section 28 is divided into a multiplicity of flow passages 47, 48, 49 and 50 of

increasing radii of curvature by means of splitter vanes 51, 52 and 53. The discharge-side core member 30 has a conical extension 54 intersecting the passages 49 and 50 and attached at its outer end 55 to the outer or convex wall of the elbow section. As the core member 54 intersects the passages 49 and 50, to avoid turbulence, it has cooperating therewith airfoil vanes 56 and 57 arranged normally with respect to the splitter vanes, the vane 56 having its opposed edges attached to the splitter vanes 52 and 53 and the vane 57 having its edges attached to the vane 53 and to the outer wall 28 of the elbow.

While the discharge end 58 of the elbow section may have any desired section or shape, as shown in Fig. 6, it is preferably made rectangular to simplify the connection thereof to the boiler housing to be supplied with air. Furthermore, with this shape of outlet, the width may be varied to provide the desired divergence, with the result that the entire passage of the blower has no precipitous change in area, the inlet passage, at 16, gradually converging and the discharge passage, at 17, together with the elbow section, gradually diverging so that velocity imparted to the air by the propeller may be efficiently converted into pressure. Aside from the flow passage serving effectively in this manner, as already pointed out, the inlet guide vanes 18, the vortex chamber 22, the circumferentially-extending vane 23, and the airfoil section discharge vanes 19 cooperate effectively to remove the rotational component due to the propeller, the pre-twist effect imparted by the inlet vanes 18 and by the vortex chamber 22 assuring that the rotational component of air leaving the propeller is both reduced and the angle thereof made substantially uniform from the hub to the blade tips, and, with substantial uniformity in the angle of discharge from the propeller, the guide vanes 19 are better able to convert the rotational component of motion of air into axial motion thereof, the discharge guide vanes 19 being of airfoil section and having rounded blunt inlet edges to permit efficient operation throughout a wide range of the angle of attack so as to convert rotary into axial motion over a wide range of variation of angle of approach of the air, such variation occurring because of change in capacity of the blower at a given speed.

Fig. 13, based on actual tests, shows the improvement both with respect to static efficiency and static pressure effected by the use of inlet and discharge guide vanes as compared to the use of guide vanes only at the discharge side or a guide vane only on the suction side. Referring to static efficiency, curve (a) for guide vanes both at the inlet and at the discharge sides represents a substantial improvement over curve (b) for guide vanes at the discharge side only and still more over curve (c) for guide vanes at the inlet side only.

The curves for static pressure show a similar relation, the curve (d) for guide vanes at both the inlet and the discharge sides showing a higher static pressure than either curves (e) or (f), curve (e) being for guide vanes on the discharge side only and curve (f) for guide vanes at the inlet side only.

These curves not only show that static efficiency is substantially improved when guide vanes are employed both at the inlet and discharge sides, but that, at the maximum static efficiency, which is normally the operating condition of the blower, the static pressure developed by the blower equipped with the com-

bination of inlet and discharge side guide vanes is about 25% higher than that obtained on the blower with discharge guide vanes only. This results in a considerable reduction of the blower 5 operating speed for the same static pressure requirements, the reduction of speed being important due to high stresses encountered in propeller blades and the hub and also because it results in reduction in noise generated by the 10 blower. Aside from the blower noise being reduced because of reduction in the operating speed, it is also reduced because the air enters the discharge guide vanes at smaller angles due to the effect of the inlet guide vanes and the 15 vortex chamber on the air entering the propeller.

A comparison of curves (a) and (b) of Fig. 13 shows that curve (a) for suction and discharge 20 guide vanes is relatively flatter than curve (b) for discharge guide vanes only, that is, a high efficiency is obtained through a wide range of blower capacities with both sets of guide vanes.

From the foregoing, it will be apparent that 25 improved performance in the respects indicated is secured due to cooperation of the various features. Referring to Figs. 11 and 12, the inlet 30 guide vanes are so curved as to impart to the entering stream of air a rotational component opposed to that given by the propeller with the result that the propeller rotational component 35 may be reduced under all operation conditions, or completely neutralized at one condition; however, as blowers customarily have an operating range, and not a single operating condition, discharge 40 guide vanes are employed to effect conversion of the residual rotational component into static pressure. The presence of inlet guide vanes imparting a rotational component to the entering air in opposition to that of the propeller improves the cooperative relation of the propeller and the discharge guide vanes in that, over 45 a range of blower capacities, the inlet guide vanes reduce the variation in the rotational component of air leaving the propeller and in consequence of which the angle of approach of air entering the discharge guide vanes is narrowed, thereby aiding in the action of the latter in dealing with the residual rotational component. As the discharge guide vanes are preferably of 50 airfoil section with round blunt inlet edges, permitting of efficient operation throughout a wide range of angle of attack of the entering air, this feature, taken with the inlet guide vanes, tending to reduce the angle, assures of efficient operation over a wide range. While the airfoil 55 guide vanes are capable of handling air discharged from the propeller with a rotational component which increases from the blade tips to the hub, thereby resulting in variation in the angle of attack of entering air from the inner to the outer ends of the discharge guide vane inlet edges, it is desirable to compensate so far as possible for this variation in order to further improve the performance or range of efficient 60 operation of the blower. Compensation is effected by means of the vortex chamber arranged between the guide vanes and the propeller, the vortex chamber functioning to impart to the air issuing from the inlet guide vanes a rotational 65 component which increases inwardly radially, but in the opposite direction with respect to the inwardly increasing rotational component of the propeller, in order to minimize the variation in the propeller rotational component from the 70 blade tips to the hub. While the vane 75 is neces-

sary to reduce pulsations, particularly where the static pressure at maximum operating speed is in excess of 15 inches of water, its effect in reducing recirculation, eddying, and shock loss in the inlet passage is conducive to improved performance of the vortex chamber. 5

The foregoing features contribute to the improved performance indicated in Fig. 13, from which it will be noted that the efficiency is improved and that the propeller speed is reduced 10 as compared to arrangements having vanes at the inlet side only and at the discharge side only. The reduction in speed is particularly important as it gives a wide margin below the critical speed when operating at high static pressures, and, as already pointed out, reduction in speed also reduces the noise level. 15

While I have shown my invention in but one form, it will be obvious to those skilled in the art that it is not so limited, but is susceptible of 20 various changes and modifications without departing from the spirit thereof, and I desire, therefore, that only such limitations shall be placed thereupon as are specifically set forth in the appended claims. 25

What I claim is:

1. In a blower, a propeller having a hub with blades carried thereby; a stator structure including a wall having close clearance with respect to the blade tips and cooperating with the hub 30 to provide an annular space for the blades; said stator structure having annular inlet and discharge passages whose adjacent ends are aligned with and close to ends of said blade space; said inlet passage converging toward the propeller 35 and said discharge passage diverging therefrom; and a circumferential series of guide vanes in the inlet passage and curved so as to impart a rotational component of motion to the air stream in a direction opposite to that imparted thereto by 40 the propeller to reduce the rotational component of motion of air discharged by the propeller; said inlet guide vanes having their discharge edges spaced from the propeller blade inlet edges and converging outwardly radially with respect to the latter and the portion of the inlet passage 45 between the guide vanes and the propeller curving inwardly and toward the propeller to provide a vortex chamber for imparting to the air stream a rotational component of motion which increases 50 from the propeller blade tips to the hub.

2. In fluid translating apparatus a propeller having a hub with blades carried thereby, a stator structure including a wall having close clearance with respect to the blade tips and cooperating 55 with the hub to provide an annular space for the blades; said stator structure having annular inlet and discharge passages whose adjacent ends are aligned with and close to ends of said blade space; said inlet passage converging toward the propeller and said discharge passage diverging therefrom; a circumferential series of guide vanes in the inlet passage for imparting a rotational component of motion to the fluid stream in a direction opposite to that imparted thereto by the 60 propeller to reduce the rotational component of motion of fluid discharged by the propeller; and circumferential vane means in the inlet passage carried by the inlet guide vanes, extending in the direction of flow, and having its discharge 65 edge arranged transversely of and contiguously to the inlet edges of the propeller blades to resist recirculation of fluid.

3. In fluid translating apparatus, a propeller having a hub with blades carried thereby; a stator 70

- structure including a wall having close clearance with respect to the blade tips and cooperating with the hub to provide an annular space for the blades; said stator structure having annular inlet 5 and discharge passages whose adjacent ends are aligned with and close to ends of said blade space; said inlet passage having a circumferential inlet spaced axially from its outlet adjacent to the blade space and, from its inlet having a large 10 component of radial direction, curving inwardly to its outlet having a large component of axial direction; a circumferential series of guide vanes in the inlet passage and curved so as to impart a rotational component of motion to the fluid stream 15 in a direction opposite to that imparted thereto by the propeller to reduce the rotational component of motion of fluid discharged by the propeller; said inlet guide vanes having their discharge edges converging radially outward with 20 respect to the plane of rotation of the propeller and spaced from the propeller blade inlet edges to provide an intermediate portion of the inlet passage serving as a vortex chamber for imparting to the fluid stream supplied to the propeller a rotational component of motion which 25 increases from the blade tips to the hub; and circumferential vane means in the inlet passage, carried by the inlet guide vanes, traversing the vortex chamber in the direction of flow, and having its discharge edge arranged transversely of 30 and contiguously to the inlet edges of the propeller blades to resist recirculation.
4. In fluid translating apparatus, a propeller having a hub with blades carried thereby; a stator structure including an outer casing and inlet and discharge core members co-axial there-with and having their adjacent ends aligned with opposite ends of the hub; said casing comprising inlet and discharge portions at the inlet and discharge sides of the propeller and an intermediate portion having close clearance with respect to the blade tips and cooperating with the hub to provide an annular blade space; said inlet portion and said inlet core member having opposed convexo-conical and concavo-conical surfaces providing, for the blade space, a converging inlet 35 passage having a circumferential inlet with a substantial component of radial direction and curving inwardly and toward its outlet having a substantial component of axial direction; said discharge portion and the discharge core member providing a diverging discharge passage for the blade space; a prime mover including a stator having spaced bearings and a rotor having a shaft 40 journaled in the bearings; said shaft and bearings being in axial alignment with said casing; the portion of the prime mover stator provided with the bearing adjacent to the propeller being telescoped with respect to the inlet core member and the rotor shaft having a portion overhanging the latter bearing with its terminal part extending beyond the inlet core member and in the space between adjacent ends of the core members; means for connecting the propeller hub to said terminal part; a circumferential series of guide vanes in the inlet passage and joining the inlet core member to the outer casing; a circumferential series of guide vanes in the discharge passage and joining the discharge core member to the outer casing; means for supporting the stator structure and maintaining it axially aligned with the propeller; and means independent of the last-named means for supporting the prime mover. 45
